Application June 3, 1954, Serial No. 434,286

3 Claims. (Cl. 193—23)

This invention relates to a distributor, and more particularly to a device for distributing color composition uniformly along the nip between a pair of calender rolls in the manufacture of sheet material such as floor and wall coverings.

In the development of unique types of graining effects in linoleum and other hard surface floor and wall coverings, it has been found that a pleasing and unusual effect can be created by feeding the linoleum composition to a pair of calender rolls at a controlled rate so as to prevent the formation of a bank of material in the nip of the calender rolls. This feeding at a controlled rate prevents the excessive churning or milling action which ordinarily takes place when the composition is fed from a bank of material disposed in the nip of the calender rolls. When the quantity of material supplied to the rolls is controlled, the exact graining formation on the finished sheet can be very accurately controlled and different graining effects can be obtained by varying the amount of material fed to the calender rolls.

However, in producing a sheet from a controlled quantity of color composition supplied to a calender, one of the main problems is to have a limited or controlled quantity of color composition disposed along the nip of the calender rolls. If the quantity of material along the nip of the calender roll is not carefully controlled, the sheet formed will not be uniform in graining or marbleizing effect; also, the sheet formed will not be a solid sheet but will have holes in areas where insufficient color composition is available to form the complete sheet.

In the production of sheet material for floor and wall coverings on conventional equipment currently used in the industry, it is not possible to distribute the material uniformly along the nip of the calender rolls without maintaining a substantial quantity of the material in a bank in the nip of the calender rolls.

One device suitable for controlling the amount of material supplied to the calender rolls is illustrated in the attached drawings, in which:

Figure 1 shows a top plan view of the composition distributing device; and

Figure 2 is a cross-sectional elevation on the line 2—2 of Figure 1.

In the formation of the unique design effects hereunder consideration, one embodiment of which is disclosed in the copending application of John W. Emig, Serial No. 434,297, filed concurrently herewith, it is necessary to produce a conventional jaspe or "Marbelle" sheet of linoleum or other hard surface covering material in the conventional manner except without a backing. This sheet is then cut into small blocks approximately $1\frac{1}{2}$ " x $1\frac{1}{2}$ " square. These blocks are fed to a sheeting calender in a controlled manner, at which calender they are consolidated into a continuous sheet. This sheet may be pressed onto a backing as it is passed through a final finishing calender, or the sheet may be formed without a backing.

2

The $1\frac{1}{2}$ " x $1\frac{1}{2}$ " blocks are fed from a chute 2 into a funnel-shaped rotating chute 3. This rotating chute 3 is mounted on a vertical shaft 4 which is driven by means not shown. This funnel is rotated at a speed of approximately 120 revolutions per minute. The blocks which are fed down the chute into the funnel 3 pass through the funnel 3 and while the funnel is rotated are distributed into a plurality of segmental chambers in a stationary device positioned immediately below the funnel and surrounding the shaft 4. These chambers are designated by the numeral 5 on Figure 1. Beneath the chambers 5 is an inclined plate 6 divided into a plurality of parallel chutes 7. In the embodiment here under consideration, sixteen of these parallel chutes are illustrated and there are sixteen chambers 5, one for each of the parallel chutes. It will be understood that the invention is not limited to the specific number shown in the embodiment here illustrated but may be varied in accordance with the requirements of the particular product being manufactured.

Each chamber 5 is in communication with one of the parallel chutes 7 through an intermediate chute 8. The bottom surface of the chambers 5 is declined, as shown at 9, so that all of the composition blocks falling into the chambers 5 will fall by gravity into the chutes 8 and will pass down through the funnel-shaped chutes 8 into the parallel chutes 7 with which the chutes 8 are in communication. With this arrangement, it will be obvious that a continuous flow of color blocks down the chute 2 will be distributed evenly to the sixteen compartments 5 by means of the rotating chute 3, and the blocks falling in each of the sixteen compartments 5 will be directed to the parallel chutes 7 so that an even distribution of color blocks will be disposed across the entire width of the machine, which is the length of the calender rolls 10 used in consolidating the blocks into a solid sheet. The calender rolls 10 are slightly in excess of six feet in length and the sixteen chutes 7 cover a span of six feet, making the width of each chute approximately $4\frac{1}{2}$ ".

At the bottom of the chutes 7 the composition blocks are directed into a trough 11 which extends substantially the entire length of the calender rolls. The trough 11 has a projection slot 12 which extends well down into the nip between the calender rolls 10. The opening 13 in the projection slot 12 is of a width greater than the thickness of the composition blocks but less than either of the other dimensions of the blocks so that the only manner in which the blocks can slide down into the nip of the calender rolls 10 is flatwise. The blocks will naturally orient themselves in a flat position as they slide down the chute 7 into the trough 11 and will maintain this flat position down through the projection 12 into the nip of the calender rolls 10. With this arrangement, a continuous supply of color blocks will be fed to the calender rolls in a uniform manner across the entire length of the calender rolls 10, but there will be insufficient material available for excessive churning or milling action at the nip. The speed of operation of the calender rolls 10 is synchronized with the speed at which the composition blocks are supplied to the chute 2. This means that only sufficient blocks are supplied through chute 2 to form a continuous sheet at the nip of the calender.

The angle at which the projection slot 12 is disposed with respect to the horizontal line is important in supplying the color composition to the nip of the calender rolls in a sufficient quantity to form a sheet with the desired surface characteristics. For example, in Figure 2, the slot 12 is disposed at an angle of approximately 60° from horizontal. If the angle is substantially less than 60° , it will be found that sliding action of the blocks is retarded and the material accumulates in the slot, re-

sulting in the feeding of material into the nip in a quantity sufficient to permit excessive milling. This excessive milling destroys the desired graining effect on the surface of the sheet material. The angle of the slot should be so adjusted that the blocks will slide down freely but be sufficiently retarded to permit the blocks to be fed to the nip of the calender rolls in a controlled overlapping relationship so that sufficient extrusion is effected by the calender rolls to form a solid sheet in which the composition blocks or particles are present and can be identified by their general configuration corresponding to the configuration of the individual blocks entering into the design.

In the particular embodiment of the invention described, the device of this invention is used to distribute blocks of color composition in a controlled manner into the nip of a sheeting calender. It will be understood, of course, that the device is also suitable for use in controlling the supply of color composition in other forms such as granulated composition or sections of extruded or cut rods, etc. Regardless of the form of color composition supplied to the slot 12, it is essential that the opening in the slot be sufficient to allow the material to pass freely therethrough but be restricted to the extent that tumbling or rolling of the composition as it passes through the slot is prevented. The angle of the slot with respect to the horizontal and the opening of the slot may be adjusted to meet the requirements of the particular composition being used, bearing in mind that sliding action of the composition with respect to the slot is essential and that tumbling or rolling action is undesirable.

It will be obvious from the disclosure herein that I have developed a device for uniformly distributing color composition across the entire nip of a sheeting calender in such manner that sufficient color composition will be fed to the nip to form a continuous sheet but the supply will be restricted to prevent excessive milling or churning action in the nip of the calender rolls.

I claim:

1. In an apparatus for producing sheet material from a plurality of individual flat color sheets, a continuously revolving chute conveying the color sheets at a constant rate; a plurality of receptacles positioned in a circular plane immediately beneath the path of travel of the end of said revolving chute, the relationship between the position of said receptacle and said chute being such that as the chute revolves it delivers an equal number of color sheets to each receptacle; and a plurality of parallel chutes leading from said receptacles to a discharge nozzle, the number of chutes corresponding to the num-

ber of receptacles, each receptacle being in communication with only one chute and each chute being in communication with only one receptacle.

2. In an apparatus for producing a sheet material from a plurality of flat color sheets, a continuously revolving chute conveying the color sheets at a constant rate; a plurality of receptacles positioned in a circular plane immediately beneath the path of travel of the end of said revolving chute, the relationship between the position of said receptacles and said chute being such that as the chute revolves it delivers an equal number of color sheets to each receptacle; a projecting slot extending to a discharge nozzle; and a plurality of parallel chutes leading from said receptacles to said projecting slot, the number of chutes corresponding to the number of receptacles, each receptacle being in communication with only one chute and each chute being in communication with only one receptacle.

3. In an apparatus for producing sheet material from a plurality of flat color sheets, a continuously revolving chute conveying the color sheets at a constant rate; a plurality of receptacles positioned in a circular plane immediately beneath the path of travel of the end of said revolving chute, the relationship between the position of said receptacles and said chute being such that as the chute revolves it delivers an equal number of color sheets to each receptacle; a projecting slot nozzle, said projecting slot nozzle being disposed at an angle of 60° with respect to a horizontal plane; and a plurality of parallel chutes leading from said receptacle to the projecting slot nozzle, the number of chutes corresponding to the number of receptacles, each receptacle being in communication with only one chute and each chute being in communication with only one receptacle.
